DIELECTRIC GENERATOR CABINET OR SIMILAR ARTICLE

Robert Farkas, Valley Stream, N. Y.

Application June 21, 1956, Serial No. 41,992

Term of patent 3½ years

(Cl. D26—5)

Fig. 1.

Fig. 2.

Fig. 1 is a perspective view of a dielectric generator cabinet or similar article, showing my new design in closed position;

Fig. 2 is a top plan view thereof; and

Fig. 3 is a perspective view thereof in open position.
I claim:

The ornamental design for a dielectric generator cabinet or similar article, substantially as shown.
